Charles E. Neydt.

UNITED STATES PATENT OFFICE.

PAUL DE MILES, OF NEW YORK, N. Y.

ELECTRIC FURNACE.

1,317,863.

Specification of Letters Patent.

Patented Oct. 7, 1919.

Application filed January 25, 1918. Serial No. 213,652.

To all whom it may concern:

Be it known that I, PAUL DE MILES, a subject of the King of Belgium, residing at 5 borough of Manhattan, city, county, and State of New York, have invented certain new and useful Improvements in Electric Furnaces, of which the following is a specification.

This invention relates to electric furnaces. 10 More particularly the invention is directed to electric furnaces of the crucible type, and constructed to readily and efficiently produce high temperatures.

A feature of the invention is the construction of the crucible of suitable electrical resistance material, electrodes therefor and means for maintaining the electrodes under pressure in contact with the resistance material. In the preferred forms of my invention 15 the crucible is mounted to be tilted or rotated, to facilitate discharge.

It is preferable to mount the furnace on the casing of the transformer in such instances where a transformer is utilized, as 20 by means of the provision of spaced arms secured to the transformer casing.

Cooling means for the electrodes, and also for the supporting arms, are also provided, when desirable.

30 Further features and objects of the invention will be more fully understood from the following description and the accompanying drawings, in which—

Figure 1 is a perspective view of an embodiment of my invention, showing the furnace mounted on a transformer casing; and

Fig. 2 is a detail central sectional view through an electrode.

Referring to the drawings, the furnace 40 proper, as illustrated, is of the crucible type, comprising the crucible proper, 1, as of carbon or the like, having the upper opening 2, and preferably with the discharge lip 3.

The electrodes 4, 5, are secured to the 45 opposite ends of the crucible 1 by means of the abutments 6, 7, attached to the respective electrodes 4, 5, and clamped by the threaded connecting rods 8, 9 having the adjusting nuts 10 to thereby hold the respective electrodes 4, 5 in good electrical contact 50 with the ends of the crucible 1. Within the perforations of the abutments 6, 7, and surrounding the rods 8, 9, are disposed washers 11 of highly insulating material

to preclude leakage or short-circuiting of 55 the electrical current.

With a crucible of carbon and cast iron electrodes, I have been able to attain the very high temperatures even in excess of 3500° F.

60 By the provision of the aforesaid pivot studs 12 on the respective abutments 6, 7, the crucible may be mounted in a pair of supporting arms 13, 14.

A handle 15 is shown in the specific embodiment illustrated in the drawings, and fixed to one stud 12, extending beyond the arm 14, whereby the crucible may be tilted and the metal discharged over the lip 3.

As one convenient form for the support 70 for the arms 13, 14, I have shown the same secured to and extending upwardly over the casing 16, adapted to contain a transformer, (not shown), the regulating arm of the resistance or impedance of the transformer 75 secondary being indicated at 17. The secondary terminals of the transformer, or the service leads when a non-transformed circuit is employed, are indicated by 18, 19 in which latter case the regulating arm 17 80 would adjust the ohmic or impedance resistance in the non-transformed circuit.

85 Preferably, the respective electrodes 4, 5 are cooled and for such purpose may be constructed hollow, with the inlet 20 and outlet 21, the former attached to the respective inflow pipes 22, supplied by the water pipe 23, whereas the outlets 21 are respectively connected to the discharge pipes 24. Such pipes 22, 24 are preferably flexible to 90 permit the furnace to be tilted, and of sufficient length and of non-conducting material to preclude leakage or short-circuiting of the current. The arms 13, 14 supporting the electrodes and therewith the crucible or 95 furnace, are respectively suitably insulated by washers or rings 25 of electrically insulating material.

100 Whereas I have described my invention by reference to specific forms thereof, it will be understood that many changes and modifications may be made without departing from the invention as defined by the appended claims.

I claim:

105 1. The combination of a plurality of spaced electrodes, a crucible wholly supported by said electrodes, said crucible com-

prising electrically resistant material adapted to be respectively engaged by said electrodes, a plurality of spaced arms corresponding to said spaced electrodes and respectively supporting said spaced electrodes and means for exerting pressure on said electrodes respectively to thereby engage said electrically resistant material.

2. The combination of a plurality of spaced electrodes, a crucible wholly supported by said electrodes, said crucible comprising electrically resistant material, adapted to be respectively engaged by said electrodes, a plurality of spaced arms corresponding to said spaced electrodes, means for rotatably supporting said electrodes on said arms respectively, and means for exerting pressure on said electrodes respectively to thereby engage said electrically resistant material.

3. The combination of a plurality of spaced electrodes, a crucible wholly supported by said electrodes, said crucible comprising electrically resistant material adapted to be respectively engaged by said electrodes, a plurality of spaced arms corresponding to said spaced electrodes and respectively supporting said spaced electrodes, means for insulating said electrodes from said arms respectively and means for exerting pressure on said electrodes respectively to thereby engage said electrically resistant material.

4. The combination of a plurality of spaced electrodes, a crucible wholly supported by said electrodes, said crucible comprising electrically resistant material adapted to be respectively engaged by said electrodes, a plurality of spaced arms corresponding to said spaced electrodes and re-

spectively supporting said spaced electrodes and adjustable common means for exerting pressure on said electrodes respectively to thereby engage said electrically resistant material.

5. The combination of a plurality of spaced electrodes, a crucible wholly supported by said electrodes, said crucible comprising electrically resistant material, adapted to be respectively engaged by said electrodes, a plurality of spaced arms corresponding to said spaced electrodes, means for rotatably supporting said electrodes on said arms respectively, and adjustable common means for exerting pressure on said electrodes respectively to thereby engage said electrically resistant material.

6. The combination of a hollow furnace having a discharge outlet, said furnace comprising electrical resistance material, spaced electrodes in electrical contact with said material, said furnace being wholly supported by said electrodes, spaced arms, means for revolvably supporting said electrodes on said arms and means for revolving said furnace.

7. The combination of a substantially cylindrical, crucible furnace having a laterally disposed discharge outlet, said furnace comprising electrical resistance material, electrodes, said electrodes being spaced from one another, mutually adjustable elements for holding said electrodes under pressure in contact with said material, spaced arms for revolvably supporting said electrodes and said furnace and means for revolving said furnace.

In testimony whereof I have signed this specification this 22nd day of January, 1918.

PAUL DE MILES.
